UNITED STATES PATENT OFFICE

2,615,300

COMBUSTION CHAMBER FOR GAS TURBINES AND HAVING FLAME TUBE MOUNTING MEANS ALLOWING RADIAL AND AXIAL EXPANSION

Adrian Albert Lombard, Clitheroe, England, assignor to Rolls-Royce Limited, Derby, England, a British company

Application March 11, 1947, Serial No. 733,911
In Great Britain April 8, 1946

6 Claims. (Cl. 60—39.32)

1

This invention relates to combustion chambers of the kind employed in aircraft gas turbine engines. More particularly this invention relates to combustion chambers of the kind comprising an elongated outer casing having an air inlet at one end, and a flame tube mounted within the outer casing. The object of the present invention is to provide improved means for supporting the flame tube in the outer casing.

According to the present invention the flame tube in a combustion chamber of the above kind is supported at each end from the outer casing with freedom for axial movement and radial expansion and means is provided for restraining at a single point on the flame tube, relative axial movement of the flame tube and the outer casing. Preferably said member also restrains relative rotational movement of the flame tube. The said means conveniently comprises a spigot and socket carried one by the outer casing and the other by the flame tube.

A specific embodiment of the invention will now be described, by way of example, with reference to the accompanying drawings whereof,

Figure 1 is a longitudinal sectional view of a combustion chamber in accordance with this invention,

Figure 2 is a view in the direction of arrow 2 of Figure 1, and

Figure 3 is a fragmentary view of a part of Figure 1 to an enlarged scale for the sake of clarity.

The combustion chamber, as shown in Figure 1, comprises a tubular outer casing 5 having an air inlet 6 at one end and a flame tube 7 mounted co-axially within the casing 5. The inlet 6 to the combustion chamber communicates with a compressor of the internal combustion turbine in known manner. The discharge end of the combustion chamber is supported as hereinafter more fully described, from a nozzle box casing 8 which also serves to support the nozzle box 9 by which the combustion products are conveyed from the chamber to the turbine.

A burner assembly generally indicated by the reference numeral 10 is mounted in the inlet end of the casing 5. Fuel is supplied to this burner from which it emerges as an atomised spray directed towards the discharge end of the combustion chamber. The air entering the inlet 6 is divided into various streams, the primary air stream passing between vanes 11 to within the flame tube whilst the secondary air passes between the casing 5 and the flame tube and enters the latter through the holes 12. Tertiary

2

air flowing between the casing and the flame tube enters the latter through the openings 13.

The burner assembly 10 has a cylindrical portion 14 projecting into the inlet end of the flame tube 7. The latter carries the vanes 11 which impart a swirling motion to the primary air. The vanes 11 carry an inner shroud 15 which fits on the cylindrical portion 14 of the burner assembly, being slid axially thereon. In this way the flame tube is supported on the burner.

The outlet end of the flame tube 7 is mounted in the outer casing 5 by means of a sheet metal band 16 which surrounds the outer surface of the flame tube and is secured thereto at one end. The other end of the band 16 is bent outwardly to be clear of the flame tube and is provided with a number of slots 17 in a hitherto known manner to form resilient fingers which bear against a ring secured to the end of the outer casing 5. In this way the flame tube 7 is located radially in the outer casing with freedom for axial movement relatively thereto. This mounting also permits of the flame tube expanding radially within the outer casing.

A dowel pin 18 is screwed into a collar 19 which is secured to the outer casing 5 towards the front end of it. The pin extends across the space between the casing 5 and the flame tube 7 and fits as a spigot in a socket 20 secured to the flame tube 7. The dowel pin 18 restrains the flame tube from both axial and rotary movements relatively to the casing 5 but imposes no restraint on expansion of the flame tube either radially or axially to each side of the pin.

It will be seen that with the present invention the flame tube 7 is supported at each end and is located at a point along its length, this construction permitting the flame tube to expand freely both radially and axially whilst being correctly located in the outer casing.

I claim:

1. A combustion chamber of the kind employed in an aircraft gas turbine engine comprising an air casing having an inlet end and outlet end, a cylindrical member secured to said air casing to lie within it at its inlet end, a flame tube having an internal cylindrical bore in axial sliding engagement with said cylindrical member, axial sliding means to support said flame tube within said air casing at the outlet end thereof, said axial sliding means being of the kind which permits radial expansion of said flame tube relative to said air casing, and locating means to locate said flame tube axially with respect to the air casing, said locating means permitting free

radial expansion of said flame tube with respect to said air casing.

2. A combustion chamber of the kind employed in an aircraft gas turbine engine comprising an air casing having an inlet end and an outlet end, a cylindrical member secured to said air casing to lie within it at its inlet end, a flame tube having an internal cylindrical bore in axial sliding engagement with said cylindrical member, axial sliding radially-deformable resilient means to support said flame tube within said air casing at the outlet end thereof, and locating means secured with respect to said air casing and engaging said flame tube to locate said flame tube axially with respect to the air casing, said locating means and said flame tube engaging each other in a manner to permit relative radial movement therebetween.

3. A combustion chamber of the kind employed in an aircraft gas turbine engine comprising in combination an elongated outer casing having an air inlet at one end and an exhaust outlet at the other end, an elongated flame-tube within said outer casing, said flame tube having an inlet end adjacent said air inlet and an outlet end adjacent said exhaust outlet, a cylindrical member secured with respect to said outer casing to lie within it in said air inlet for supporting said flame tube, a sleeve formed on the inlet end of said flame tube having an internal cylindrical bore to receive said cylindrical member with freedom for relative axial movement between said cylindrical member and said flame tube at said inlet end, second supporting means secured with respect to said outer casing for supporting said flame tube at said outlet end with freedom for relative axial movement between said second supporting means and said flame tube at said outlet end, said second supporting means being of the kind which permits radial expansion of said flame tube relative to said air casing, and locating means secured with respect to said outer casing and engaging said flame tube at a single place between said first and second supporting means to prevent axial movement relative to said outer casing of said flame tube at said single place.

4. A combustion chamber of the kind employed in an aircraft gas turbine engine comprising an air casing having an inlet and an outlet end, a cylindrical member secured to said air casing to lie coaxially within it at its inlet end, a flame tube having an internal cylindrical bore coaxial with the flame tube and in axial sliding engagement with said cylindrical member, axial sliding means to support said flame tube within said air casing at the outlet end thereof, said axial sliding means being of the kind which permits radial expansion of said flame tube relative to said air casing and locating means to locate said flame tube axially with

respect to said air casing, said locating means permitting said flame tube to expand radially relatively to said air casing.

5. A combustion chamber of the kind employed in an aircraft gas turbine engine comprising an air casing having an inlet end and outlet end, a cylindrical member secured to said air casing to lie within it at its inlet end, a flame tube, having an internal cylindrical bore in axial sliding engagement with said cylindrical member, axial sliding means to support said flame tube within said air casing at the outlet end thereof, said axial sliding means being of the kind which permits radial expansion of said flame tube relative to said casing, a radially-inwardly-extending dowel secured to said air casing, and a radially-outwardly-extending socket secured to said flame tube and receiving said dowel, whereby said dowel and socket locate said flame tube axially with respect to said air casing and permit relative radial expansion between said flame tube and said air casing by sliding of the dowel within the socket.

6. A combustion chamber of the kind employed in an aircraft gas turbine engine comprising an air casing having an inlet end and an outlet end, a cylindrical fuel injector secured to said air casing to lie within it at its inlet end, a flame tube having an internal cylindrical bore in axial sliding engagement with said fuel injector, axial sliding means to support said flame tube within said air casing at the outlet end thereof, and locating means to locate said flame tube axially with respect to said air casing, said axial sliding means and said locating means being of the kind which permit radial expansion of said flame tube relative to said air casing.
